UNITED STATES PATENT OFFICE.

GEORGE L. KOLLOCK AND SAMUEL W. M. KOLLOCK, OF SEATTLE,
WASHINGTON.

JACK-SCREW.

SPECIFICATION forming part of Letters Patent No. 691,061, dated January 14, 1902.

Application filed April 28, 1901. Serial No. 57,096. (No model.)

To all whom it may concern:

Be it known that we, GEORGE L. KOLLOCK and SAMUEL W. M. KOLLOCK, citizens of the United States, residing at Seattle, in the county 5 of King and State of Washington, have invented certain new and useful Improvements in Jack-Screws, of which the following is a specification.

Our invention relates to improvements in 10 jack-screws; and among numerous objects attained thereby and readily understood from the accompanying drawings and following specification are simple and efficient means for raising and lowering the screw, like means 15 for raising a load when resting at the base of the jack, and preferred structural features incidental to the embodiment of the objects.

With reference to the drawings, included 20 as a part of the specification, Figure 1 is a perspective view of the jack with the screw slightly advanced. Fig. 2 is a transverse section of same on line 6 7, Fig. 1. Fig. 3 is a plan view of the ratchet-lever, with one arm removed to disclose the pawls and the ratchet- 25 nut. Fig. 4 is a broken elevation of the jack, disclosing modified means for driving the nut; and Fig. 5 is a diametrical section of the nut.

Like characters of reference designate corresponding parts throughout the several views 30 of the drawings.

In the present embodiment the reference character A indicates the stand; B, the screw; C, the nut; D, the ratchet-lever, and E a two-part head for the screw.

35 The screw B comprises a suitable bar conveniently formed with a square screw-thread, as in the ordinary manner, and having its lower extremity conveniently formed for the attachment of a foot, as a. This foot is firmly 40 fixed to the screw and extends laterally therefrom with suitable projections from the side of the stand A and is preferably formed with a head, as 14², having a groove, as b, extended across each side face and adapted to slidably 45 embrace guides d, placed longitudinally the stand A, thereby holding the foot slidably rigid, relieving the screw of cross-strain, and holding it from turning with the nut. The foot is also preferably formed with an angular bottom surface 16, which renders the toe 50 thereof wedge-shaped and permits the foot to

be more readily worked under objects resting at the base of the jack.

As now considered, the stand A is made with a suitable head h, a longitudinally-extended recess, as f, in one side face, and suitable apertured lugs 10 at the base, which are placed for convenience in fastening the jack by suitable stays, and a suitable handle 12 is fixed adjacent the top for obvious purposes. 55 The recess f extends to the bottom of the stand and is adapted to receive the screw B and head of the foot a, and the guides d are conveniently fixed longitudinally the side walls thereof, so as to engage with the grooves 60 in the head of the foot a, and said head is preferably made to also slidably fit against the back wall of the recess to more rigidly position the foot, as indicated in Fig. 2.

The head of the stand A is conveniently 70 provided with a suitable concentric aperture through which the screw B works as promoted by operations of the nut C, which is formed with suitable screw-threads fitting the thread of the screw and is supported upon 75 the head h by a suitable ball-bearing of any ordinary or desired construction adapted to reduce frictional resistance.

In the preferred embodiment the nut C is 80 conveniently formed with suitable ratchet-teeth on its periphery and with hubs, as 14, which adapt it for movement by the ratchet-lever D. This lever is suitably bifurcated at the inner end to embrace the nut, and each 85 bifurcation is provided with a suitable aperture to fit it to a hub 14, whereby the lever is adapted to move about the nut during its return movement, as in ordinary ratchet contrivances of like class.

Between the bifurcations of the lever D are 90 conveniently pivoted right and left pawls, as k and k', which are suitably spring-pressed to engage the teeth on the nut c in the ordinary manner and have extended shanks, as 95 15, whereby either one can be forced against spring-pressure and made to lie from engagement with the teeth on the nut, and thereby adapt the lever for rotating the nut in either direction, as determined by the setting of the pawls. The pawls are conveniently and expeditiously set by means of a yoke, as f, which is fixed to an operable pivot 20, conveniently

journalled in the lever to cause the yoke to embrace the extremities 15 of the pawls. This pivot is extended beyond the upper face of the lever and bent to afford a handle 21, by which the yoke is manipulated to set the pawls, and a lock-pin, as 22, is removably seated in the lever at desired points to conveniently secure the position of the yoke when turned to hold either pawl from the nut.

- 10 In the present instance the pawls *k* and *k'* are suitably pressed to engage the teeth on the nut *C* by means of independent flat springs, as 13 and 17, resting between the pawls and fixed by one end to the lever and pressing with their free ends upon the extremities of the respective pawls as opposed to movement of the pawls by the yoke *F*.
- 15

Fig. 4 indicates modified means for impelling the nut *C* to action by a force applied at right angles to its movement, and consists of a modified form of nut *D'*, having its periphery conforming to that of a bevel-pinion and a driver thereof comprising a bevel-wheel *G*, which is journalled to the frame *A* by a suitable pivot, as *g*, and carries a handle, as 23, by which it is made to rotate the nut rapidly and continuously.

The head *E* of the screw consists of two parts, as 25 and 26, the former being suitably fixed to the end of the screw, and its upper surface is made substantially level, as in ordinary practice, while the latter is detachably mounted on the former in any suitable manner and is formed with a concave upper surface to adapt it for lifting shafts, axles, and the like.

It will be understood that the foot *a* is adapted for exerting force at points where it would be impossible to use the head *E*, as it can be brought to the bottom of the stand *A*,

and thereby engage with the objects resting on the same surface by tilting the jack slightly, as permitted by the angular surface 16 at the toe of the foot, and working the foot under the object, when the jack is returned 45 and the nut rotated to lift the load.

A jack-screw thus produced is simple and positive in operation, powerful in action, and adapted for applying force in various ways not covered by the ordinary jack. Furthermore, the ratchet contrivance embodied with the lever is exceedingly simple and inexpensive and easily adjusted to reverse the travel of the nut.

Having thus described our invention, what we claim, and desire to secure by Letters Patent of the United States, is—

In a jack-screw, the combination of a stand having a longitudinal recess, a head and guides, a foot having a screw and a head with 60 grooves to receive said guides, a nut on said screw and supported by the head of the stand, and having ratchet-teeth and hubs upon opposite sides thereof, a ratchet-lever bifurcated and having portions embracing said hubs, 65 pawls mounted in the bifurcation of the lever, a yoke pivoted in the bifurcation of the lever to engage said pawls, the pivot of the yoke being extended to form a handle, and a lock-pin removably inserted in the lever for 70 coöperation with said handle, all substantially as shown and described.

In testimony whereof we affix our signatures in presence of two witnesses.

GEO. L. KOLLOCK.
SAMUEL W. M. KOLLOCK.
